WILLIAM SELBY AND RENÉ PAUL MAGNENAT, OF WATERBURY, CONNECTICUT, AS
SIGNORS TO WATERBURY BUTTON COMPANY, OF WATERBURY, CONNECTICUT, A COR-
PORATION OF CONNECTICUT

TOY BANK AND VENDING MACHINE

Application filed April 20, 1929. Serial No. 356,852.

This invention relates to coin-controlled vending devices, and more particularly to a toy bank adapted to deliver an article of value, such as a stick of chocolate, each time that a child deposits a coin therein.

One object of this invention is to provide a coin-controlled bank of the above nature in which the article to be delivered is carried in a pull drawer which is normally held closed by a latch lever pivotally mounted thereon and engaging a portion of the casing of the bank, said drawer being released by the falling of the coin upon said lever.

A further object is to provide a device of the above nature which will be simple in construction, inexpensive to manufacture, easy to install and manipulate, compact, ornamental in appearance, and very efficient and durable in use.

With these and other objects in view there has been illustrated on the accompanying drawings one form in which the invention may be conveniently embodied in practice.

Fig. 1 represents a vertical sectional view of the toy vending bank.

Fig. 2 is a perspective view of the pull drawer for delivering the vended article.

Fig. 3 is a fragmentary sectional view of the bank with the pull drawer shown in open position.

Fig. 4 is a perspective view showing the general appearance of the bank with the side door thereof in open position.

Referring now to the drawings in which like reference numerals denote corresponding parts throughout the several views, the numeral 10 indicates a box-shaped casing having a curved cover 11 shaped to imitate the roof of a small house, and a flanged base 12 for simulating the foundation of said house. Mounted within the casing 10 is a downwardly and rearwardly inclined coin chute 13 having its upper forward end located slightly below and in alinement with

a coin-insertion opening 14 in the front of the casing 10.

The rear part of the coin chute 13 is vertical and lies adjacent and parallel to the rear of the casing 10. In order to guide the coins in their downward travel, provision is made of a U-shaped vertical member 15 located between the rear of the chute 13 and the rear of the casing 10 and forming a passageway 16. The bottom end of the passageway 16 is in alinement with the rear reduced section 17 of a latch lever 18 having a pair of oppositely extending lugs 19 for pivotal engagement in suitable sockets formed in a pair of ears 20 depending from the rear section of a pull drawer 21.

The forward part of the latch lever 18 is provided with a depending vertical latch 22 normally designed to be locked within a slot 23 in a partition member 24 secured in the casing 10 near the bottom thereof. As will be understood, the space below said partition member 24 comprises the bank proper, or in other words, a receptacle for the coins deposited by the child.

The rear section 17 has a downwardly and forwardly inclined catch 25 which is adapted to be engaged by a cooperating upwardly and rearwardly inclined lug 26 struck up from the metal of the partition 24 and located at the rear of the slot 23. The catch 25 and the lug 26 serve to prevent the drawer 21 from being pulled out too far, or in other words, beyond the article-delivering position shown in Fig. 3.

In order to prevent more than one candy article from being delivered at one operation of the device, the forward section of the drawer 21 is off-set downwardly at 28 for a distance equal to the height of said article 27, such as a piece of chocolate, and said drawer has an upstanding forward end 29 provided with a drawer pulling knob 30 for convenience in manipulation.

An angular plate member 31 is provided

in the bank above the partition 24 and has a vertical portion 32 for confining the candy pieces 27 in a storage space at the front of the casing in position to be visible through a glass window 33. The plate member 31 has a horizontal rearwardly extending base 34 which forms a guideway for the top of the drawer 21. The coins which collect in the receptacle at the bottom of the bank 10 are made proof against unauthorized removal by a door 35 pivotally connected to one side of the casing 10 by a hinge 36, said door having a key-operated lock 37 mounted thereon. The lock 37 has a latch bar 38 adapted to engage behind a vertical flange 39 extending along the front side of the door frame of said casing 10.

Operation

20 In operation, when the child deposits a coin in the slot 14, it will slide down the coin chute 13 and drop through the vertical passageway 16, striking the rear section 17 of the latch lever 18. The latch lever 18 is so designed that the weight in front of the pivot lugs 19 will overbalance the weight behind said lugs, whereby the rear reduced section 17 will normally remain in its uppermost position, as shown in 25 Fig. 1. The weight of the coin on the rear reduced section 17 of the lever 18 will cause it to tilt downwardly to the position shown in Fig. 3, disengaging the latch 22 from the slot 23. The child will then grasp the handle 30 and pull the drawer 21 out to the position shown in Fig. 3, the depressed forward section 28 of said drawer carrying a piece of candy 27, which is then removed by the child. This action permits the coin 30 to drop down into the receptacle below the partition 24. Since the lowermost remaining piece of candy 27 will then rest on the rear of the drawer 21, it will be seen that it will be impossible to remove more 35 than one piece at a time. When the drawer 21 is pushed back far enough to permit another piece of candy 27 to drop into the depressed forward section 28 of the drawer, the latch 22 will already have dropped down 40 again into the slot 23. The drawer will then be locked in its original condition and the device will be ready for another operation.

While there has been disclosed in this 55 specification one form in which the invention may be embodied, it is to be understood that this form is shown for the purpose of illustration only, and that the invention is not to be limited to the specific disclosure 60 but may be modified and embodied in various other forms without departing from its spirit. In short, the invention includes all the modifications and embodiments coming within the scope of the following claims.

65 Having thus fully described the invention,

tion, what is claimed as new, and for which it is desired to secure Letters Patent, is:

1. In a toy vending bank, a casing, a coin-conveying chute, a slidable pull drawer for containing a vendible article, a lever pivotally mounted on said drawer, said lever having a depending latch on its forward end, said casing having a slot located below said latch when said drawer is closed for normally preventing the withdrawal thereof, the rear end of said lever having a locking latch for engaging said casing to prevent complete withdrawal of said drawer, said rear end being normally situated beneath and in alignment with the bottom discharge end of said coin chute, whereby the falling of a coin will cause the latch to be disengaged from said catch permitting the manual withdrawal of said pull drawer for removal of the article therefrom. 70

2. In a toy vending bank, a casing, a coin-conveying chute, a slidable pull drawer for containing a vendible article, a lever pivotally mounted on said drawer, said lever having a depending latch on its forward end, said casing having a catch section located below said latch when said drawer is closed for normally preventing the withdrawal thereof; the rear end of said lever being normally situated beneath and in alignment with the bottom discharge end of said chute, whereby the falling of a coin will cause the latch to be disengaged from said catch permitting the manual withdrawal of said pull drawer for removal of the article therefrom, the rear end of said lever having a locking latch, and said casing having a lug for engaging said rear latch to lock said drawer against being withdrawn entirely out of said casing. 75

3. In a toy vending bank, a casing, a coin-conveying chute, a slidable pull drawer for containing a vendible article, a lever pivotally mounted on said drawer, said lever having a depending latch on its forward end, said casing having a catch section located below said latch when said drawer is closed for normally preventing the withdrawal thereof, the rear end of said lever being normally situated beneath and in alignment with the bottom discharge end of said coin chute, whereby the falling of a coin will cause the latch to be disengaged from said catch permitting the manual withdrawal of said pull drawer for removal of the article therefrom, the rear end of said lever having a depending locking latch, and said casing having an upstanding lug for engaging said rear latch to lock said drawer against being withdrawn entirely out of said casing. 80

4. In a toy vending bank, a casing, a coin-conveying chute, a partition near the bottom of said casing, a pull drawer slidable upon said partition, said pull drawer having a raised rear section, a pair of ears depend-

ing from said rear section, a coin-released latch lever having oppositely extending lugs journaled in said ears, said lever having a depending latch at its forward end, and having its rear end in alinement with said chute, said partition having a slot for normally engaging said latch, for preventing withdrawal of said pull drawer until a coin is inserted in said chute, and cooperating means on said drawer and partition for preventing complete withdrawal of said drawer.

In testimony whereof, we have affixed our signatures to this specification.
